This invention relates to the technique of sound absorbing, for example, in silencing workshops, offices, cinemas and other places wherever noise is to be absorbed and acoustical reverberations are to be prevented.

Modern techniques in sound absorbing employ multiple-resonator panels based on the principle of Helmholtz's resonators, which have a remarkable sound absorbing power. However, such panels are relatively expensive. Their great cost prevents their use to any large extent in small industries and handicraftsman workshops, for example.

A principal object of the present invention is to provide a sound-absorbing covering or sound-absorber of the multiple-resonator type, which is relatively cheap and at the same time possesses a high absorbing power with regard to low and high acoustical frequencies.

Another object of the invention is to provide a sound-absorber suitable to be tuned to a relatively large band of low frequencies, according to the circumstances, without prejudice for its absorbing power with regard to higher frequencies, superior to about 2000 c./s.

According to the invention, the covering includes, in combination with a ceiling or wall of a space or room, a rigid plate corrugated or undulated with substantially trapezoidal-wave shaped undulations. The plate or undulated member is fixed to a wall in parallel spaced relation to the latter thereby to provide parallel channels open towards the said wall alternating with channels opening freely towards the space. A relatively great number of apertures of relatively small areas in the bottom of each of the channels open towards the wall, and a relatively small number of apertures of relatively large areas in the bottom of the channels open towards the space or room with a filling of a fibrous material in those channels only which open towards the wall.

The corrugated or undulated member is preferably moulded in fibre-cement, but also other materials can be used, such as metals or synthetic resins, provided they confer to the plate a sufficient indeformability under its own weight and that of the fillings.

According to an important and advantageous feature of the invention, each outside flank or outermost portion of each extreme channel presents a height or cross-sectional length greater than the depth of the remaining channels and ends with a fitting flange to the wall. The two flanks provide therefore spacing members between the plate and the wall.

In case of plates of substantial dimensions, the bottom of an intermediate channel open towards the room can be heightened with respect to the general level of the member to the level of the two fitting flanges thereby to provide for an intermediate anchorage of the plate to the wall. This is particularly advantageous in the case in which the plate is fixed to the ceiling of the room.

The spacing of the plate with respect to the wall pro-

2

vides a cavity between the plate and wall bridging a selected number of channels open towards the wall forming a resonant case which is common to all the apertures in the bottom of such channels.

5 The response to low frequencies depends on the number of these apertures, their diameter and the volume of the cavity mentioned above. The volume of the spaces is in turn a function of the distance between the plate and the wall. The greater the distance, the lower the mean frequency of the absorbed band. Thus, by interposing between the fitting flanges on the plate and the wall suitable shims, not shown, it is possible to tune the device according to the invention on any band of low frequencies included between about 80 c./s. and about 2000 c./s.

10 Other features and advantages of the invention will result from the following description with reference to the appended drawings, in which:

FIGURE 1 is a sectional perspective view of an embodiment of this invention applied to a ceiling of a room; FIGURE 2 is a cross-sectional view of another embodiment.

In the drawings, similar reference numbers indicate equal or equivalent parts.

Reference 10 indicates a ceiling of a room to which 25 is secured by means of nails 11 a plate 12 moulded in cement-asbestos. This material is found particularly advantageous because, besides assuring to the plate a good self-support, it presents also a great inertia with regard to acoustical vibrations and so it seldom resonates. In other words, this material has a high inner friction, which 30 damps every incipient acoustical vibration. In general, the plate thickness is between two and four millimeters depending on its dimensions. The plate is rectangular in plan and is corrugated to a trapezoidal wave shape 35 forming channels 12a which open downwardly, that is towards the space or room in which sound absorbing is to take place, alternating with channels 12b which open towards the ceiling 10. In each channel 12b is placed a mineral fiber sliver 13 which fills its respective channel to a level not higher than that of the bottoms 14 of the downwardly open channels 12a. Such sliver is preferably glued to the walls of the respective channel by means of any suitable adhesive. The first channel on the right 40 in FIGURE 1 is shown without the respective fibrous filling, thereby to render visible two longitudinal rows of circular apertures 15 in the bottom 16 of the channel. Such apertures are provided in all the channels 12b. The apertures 15 have each a relatively small diameter and 45 are relatively close to one another.

50 In the bottom 14 of each channel 12a open towards the room one row only of circular apertures 17 of a relatively large diameter is provided, the apertures 17 being appreciably spaced from one another. So, considering the volume of the channels 12b open towards the ceiling, each aperture 15 has associated therewith a relatively 55 small fraction of such volume. On the contrary, considering the volume of the free space between the plate 12 and the ceiling 10, to each aperture 17 corresponds a relatively great fraction, several times greater (in volume units) than that corresponding to each aperture 15.

The flanks 18, 19 of the two extreme channels 12b open towards the ceiling 10 extend upwardly beyond the common plane of the bottoms 14 of the channels 12a open

towards the room and each of them ends as a flange 20 by which the nails 11 fasten the plate to the ceiling.

The height of the flanks 18, 19 determines therefore the smallest distance between the plate and ceiling. The practical effects, considering the diameter and distribution density of the apertures 17 in the bottoms 14 of the downwardly open channels 12a are such that the smallest distance should be determined to obtain with regard to relatively low acoustical frequencies (40-2000 c./s.), the highest absorption within the band adjacent the high limit of these frequencies, such as the band 800-2000 c./s. for example. In this manner frequencies which are less than 800 c./s. will be absorbed somewhat less efficiently, which does not present, however, any inconvenience in practice. So, for example, in a case in which the sound or noise to be absorbed presents a maximum frequency of 200 c./s., the distance between the plate 12 and the ceiling 10 can be easily increased by interposing between the flanges 20 and the ceiling listels or strips of wood, not shown, of suitable thickness. In such a way, the plates 12 can be moulded in a single standardized dimension. In practice, before application, the usual preliminary phonometric measurements will reveal the band in the field of low frequencies prevailing in the room to be sound insulated, whereupon the thickness of the spacing listels may be determined.

The plates 12 can present relatively great dimensions, when measured transversely of the channels. In such a case, to prevent the plates from bowing downwardly, the flanks 22, 22' (FIGURE 2) of an intermediate channel 12'a can extend upwardly so that the bottom of this channel is at the level of the terminal fastening flanges 20 of the plate, whereby said bottom too can be nailed to the ceiling.

Apparently, in comparison with "multiple-resonator" panels, the operation of the present sound-absorbing covering is not based exclusively on the Helmholtz's resonance effect. Presumably a following interpretation is valid.

Sound waves of a relatively high frequency are more "directional" than those of a relatively low frequency. Furthermore, absorption of relatively high frequencies does not involve a particular selectivity of the absorbing medium or means: in other words, all the frequencies between about 2000 c./s. and about 10,000-15,000 c./s. are absorbed substantially to the same degree (in general satisfactory) by means of a suitable layer of mineral or vegetable fibers.

In the specific case, high frequency waves are received by the very high number of apertures 15 and, subdivided into separate wave fronts, conveyed towards the heaps of fibres 13. The "directionality" of high frequency waves gives here rise to innumerable reflections and deflections of the single wave fronts with consequent dissipation on their energy principally by way of the fibers and secondarily by way of resonators formed by the channels 12b containing the fibers.

On the contrary, a quite different situation arises in the field of low frequencies, up to about 1800-2000 c./s., which are very little "directional" and usually require rather "selective" absorbing means. This is one of the reasons for which low frequencies are not absorbed appreciably by the usual fiber mattresses and for which the resonant systems must be at least roughly "tuned" to that low frequency band which prevails in the field 40-2000 c./s.

The channels, which are trapezoidally shaped, allow extension remarkably of the limits of such band, without a notable drop in absorption factor, as is known in the art. However, in the present case, the trapezoidal channels 12a open towards the ambient and destined to "manipulate" the low frequencies seem to work as resonators in a very limited degree only; actually, they rather "compress" the low frequency waves, leading them towards the relatively large apertures 17, while the extinction of such waves due to resonance is carried out by the "air-case" formed between the plate 12 and the ceiling 10.

The air volumes delimited by each bottom 14, the ceiling 10 and the imaginary planes indicated with 30 and 31 in FIGURE 1 define in this air-case virtual primary resonators, in which a great proportion of the energy contained in low frequency waves is extinguished. A part of these waves is reflected by the ceiling 10 towards the channels 12b open towards the ceiling and which form together with the latter secondary resonators, they too virtual because delimited partly by the imaginary planes 31, 32 (FIGURE 1).

Of course, the exact position of the planes 30, 31, 32 can be different from that shown for illustrative purposes. FIGURE 1 clearly shows that the volume of these virtual secondary resonators is greater than that of primary resonators, and this fact is very favourable to the effects of the present invention; in fact, due to the virtuality of the planes 30, 31 delimiting the primary resonators, only the acoustical components still having a certain directional character easily form stationary waves between the bottom 14 and the ceiling 10, while the less directional components escape and spread laterally. But such less directional components have the lowest frequency among all frequencies present and the highest volumes of the virtual secondary resonators are just the most suitable means for their absorption.

The above theory explains also both the necessity of a free space between the plate 12 and the ceiling 10, which bridges a number of channels 12b, and the capacity of the present sound-absorbing covering to absorb a large band of low frequencies even with an only rough tuning.

It is to be understood that the above theory does not limit the scope of this invention and should be considered only as an attempt of a logical interpretation of the phenomena discovered in laboratory tests on the above described coverings.

What we claim is:

1. A sound-absorber comprising, an undulated member of substantially rigid sheet material having undulations defining a plurality of adjacent parallel channels of a substantially trapezoidal cross-sectional shape, all of said channels having a small base ridge defined by said undulated member and alternate ones of said channels having a large base area opening in a common direction, said member having two outermost portions each defining a side of respective channel and each having a longer cross-sectional length than the remaining undulations of said member, each of said outermost portions having a flange for securing said sound-absorber to a wall or ceiling defining a space between the sound-absorber or wall, and the channels opening toward said space comprising a sound-absorbing filling therein.

2. A sound-absorber comprising, an undulated member of substantially rigid sheet material having undulations defining a plurality of adjacent parallel channels of a substantially trapezoidal cross-sectional shape, all of said channels having a small base ridge defined by said undulated member and alternate ones of said channels having a large base area opening in a common direction, said member having two outermost portions each defining a side of a respective channel and each having a longer cross-sectional length than the remaining undulations of said member, each of said outermost portions having a flange for securing said sound-absorber to a wall or ceiling defining a space between the sound-absorber or wall, and the channels opening toward said space comprising a sound-absorbing filling therein, and the ridges of said undulations each having a plurality of spaced, through apertures therein.

3. A sound-absorber comprising, an undulated member of substantially rigid sheet material having undulations defining a plurality of adjacent parallel channels of a substantially trapezoidal cross-sectional shape, all of said channels having a small base ridge defined by said undulated member and alternate ones of said channels

having a large base area opening in a common direction, said member having two outermost portions each defining a side of a respective channel and each having a longer cross-sectional length than the remaining undulations of said member, each of said outermost portions having a flange for securing said sound-absorber to a wall or ceiling defining a space between the sound-absorber or wall, and the channels opening toward said space comprising a sound-absorbing filling therein, the ridges of said undulations each having a plurality of spaced through apertures therein, and said sound-absorbing filling being

disposed substantially flush with the ridges of the undulations defining the channels in which said filling is disposed.
